United States Patent Office

Des. 219,376
Patented Dec. 8, 1970

219,376

CHAIR

Maxwell E. Pearson, Zionsville, Pa., assignor to Art Metal-Knoll Corporation, New York, N.Y., a corporation of Delaware

Filed Sept. 16, 1968, Ser. No. 13,539

Term of patent 14 years

Int. Cl. D6—01

U.S. Cl. D15—1

FIG. 1 is a perspective view of an arm chair embodying the new design.

FIG. 2 is a rear view of the chair of FIG. 1.

The essential features of the chair reside in the full line portions.

I claim:

The ornamental design for chair, as shown and described.
